COMBINED BOOT AND FILLER INSERTING TOOL
FOR SEWN-IN BICYCLE TUBE TIRES OR THE
LIKE

Philip Joseph Quartararo, 2309 Avenue Y, Brooklyn, N.Y.

Filed Aug. 27, 1964, Ser. No. 81,474

Term of patent 3½ years

(Cl. D54—13)

FIG. 1

FIG. 2

FIG. 3

FIG. 4

FIG. 1 is a front elevational view of a combined boot and filler inserting tool for sewn-in bicycle tube tires or the like embodying my new design, the rear elevational view being identical;

FIG. 2 is a side elevational view thereof, the other side being identical;

FIG. 3 is an enlarged top plan view thereof; and
FIG. 4 is an enlarged bottom plan view thereof.

I claim:

The ornamental design for a combined boot and filler inserting tool for sewn-in bicycle tube tires or the like, as shown and described.
